UNITED STATES PATENT OFFICE

2,667,762

CONDENSER FOR REFRIGERATING SYSTEMS

James R. Hornaday, North Muskegon, Mich., assignor to Borg-Warner Corporation, Chicago, Ill., a corporation of Illinois

Application April 26, 1951, Serial No. 223,084

2 Claims. (Cl. 62—117.4)

1

This invention relates in general to refrigerating apparatus and has particular reference to an improved form of condenser construction which, for example, is advantageously adaptable for employment in refrigerating systems of the type wherein a refrigerating medium is circulated through a closed system and is successively compressed in a gaseous state, condensed into a liquid and then expanded by evaporation by a relatively high pressure. The condenser of the present invention, in addition to its inherent improved heat transfer characteristics, is particularly characterized by the provision of an effective and improved refrigerant cooling arrangement directly and operatively associated with the condenser proper.

Otherwise stated, the invention is embodied in a condenser particularly arranged to provide for the minimizing of the transference of heat from the motor to the compressor and to the sealing and/or lubricating liquid and in connection therewith to produce and maintain, to as perfect a degree as possible, adiabatic compression.

More specifically stated, it is an object and accomplishment of the invention to provide an improved condenser, said condenser embodying structure wherein the motor of the compressor is cooled by contact with gaseous refrigerant discharged from the compressor and whereby the flow of the refrigerant is controlled and directed in proximity to the motor of the compressor in a sufficient volume to provide adequate cooling of the motor by the gaseous refrigerant as will be manifest by the detailed description following hereinafter.

Another important object and accomplishment of the invention is to provide an improved condenser for a refrigerating system by eliminating expensive finned prior art condenser constructions and employing a plurality of relatively inexpensive rods disposed in thermal contact with the refrigerant tubes of the condenser, this construction affording a substantial reduction in the cost of manufacture and yet providing more efficient dissipation of heat by convection.

Another object and accomplishment of this invention is to provide a refrigerating system in which the superheat is removed from the compressed gas before being discharged into the lubricant separating chamber.

A further object and accomplishment of the invention is to provide an improved refrigeration system having incorporated therein provision for motor and compressor cooling and, in addition thereto, an improved condenser, said improved elements cooperating and being effective to pro-

2

duce efficient oil separation so that oil is kept out of the low side of the system and the efficiency of the system is not reduced by circulating large amounts of oil through the evaporator.

An ancillary object and accomplishment of the invention is to provide a more efficient refrigerating system having incorporated therein a new and improved condenser which is adapted to be economically manufactured and which is so designed as to permit the manufacture and assembly thereof in accordance with present day large scale mass production manufacturing methods of construction and assembly.

The invention seeks, as a final object and accomplishment, to provide a refrigerating system which includes an improved condenser particularly characterized by a design arrangement to more advantageously and satisfactorily perform the functions required of it and adapted to provide a compact unit which will successfully combine the factors of structural simplicity and durability and yet be economical to manufacture.

Additional objects, features and advantages of the invention disclosed herein will be apparent to persons skilled in the art after the construction and operation are understood from the within description.

It is preferred to accomplish the various objects of this invention and to practice the same substantially as hereinafter more fully described, and as more particularly pointed out in the appended claims.

Embodiments of the invention are illustrated in the accompanying drawings forming a part hereof and wherein:

Fig. 1 is a side elevational view of a part of a refrigeration system and disclosing the condenser embodying the features of the present invention;

Fig. 2 is a front elevational view of the condenser depicted in Fig. 1;

Fig. 3 is a fragmentary perspective view of the condenser depicted in Fig. 1 and illustrating the specific association of the parts of the condenser;

Fig. 4 diagrammatically illustrates a refrigeration system in which the condenser contemplated by this invention may advantageously be employed;

Fig. 5 is a fragmentary sectional view of the condenser tubing and rod arrangement depicted in Fig. 3;

Fig. 6 is a fragmentary sectional view of a modified form of condenser tubing and rod arrangement; and

Fig. 7 is a fragmentary view of a conventional

prior art finned condenser illustrating the path of air flow therethrough by convection.

The drawings are to be understood to be more or less of a schematic character for the purpose of illustrating and disclosing typical or preferred forms of the improvements contemplated herein and in the drawings like reference characters identify the same parts in the several views.

Referring to the drawings, particularly Figs. 1 and 4, there is illustrated a sealed motor compressor unit designated in its entirety by the letter A and including a motor housing indicated at 20 and a compressor housing indicated at 21.

The sealed motor compressor unit A may comprise a part of a refrigerating system of the compressor-condenser-expander type, such as diagrammatically illustrated in Fig. 4, and wherein the refrigerant is circulated by means of the compressor disposed in the housing 21, through a condenser indicated in its entirety by the numeral 30 and with which the present invention is particularly concerned, for extracting or dissipating heat by convection from the refrigerant medium and thence to a freezer or evaporator B in which the refrigerant medium is expanded or vaporized for absorbing heat and the refrigerant medium is thereafter returned to the compressor from whence the cycle is repeated.

Suffice it to say, since the invention is not particularly concerned with the precise construction of the complete refrigerating system and/or its associated parts, they will not be further described in detail, and it is deemed sufficient for all intentions and purposes herein contained to show only portions thereof adjacent to and co-operating with the condenser 30 with which the invention is particularly concerned. It is to be understood that details of construction of such refrigerating systems and/or their associated parts may be modified to suit particular conditions or to satisfy the engineering genius of various competitive manufacturers, and I do not wish to be limited to the construction of these elements as set forth except where such construction particularly concerns the invention contemplated herein.

Having thus described, by way of example, a possible adaptation of the condenser 30 and having described the general environment surrounding the adaptation, the specific construction and function of the parts of said condenser when disposed in the refrigerating system hereinbefore described, will now be described in detail.

In general, it may be stated, that an ancillary function of the improved condenser construction contemplated by this invention is to act as a cooling device for the motor of the motor compressor unit.

This is advantageously accomplished by the provision of the cooling coil 31, portions of which are directly associated with the condenser 30 and interconnected with the compressor 20 and which are so arranged to receive the refrigerant directly from the compressor in a first phase of operation wherein there are employed principles of operation whereby the superheat of the refrigerant gas is unloaded by convection in the ambient outside the compressor proper by means of the cooling coil 31, the unloading of the superheat of the refrigerant to the air in this manner offering the advantages of not adding unnecessary heat to the motor disposed within the motor housing 20 of the motor compressor A, thereby permitting the motor to run cooler. The cooling coil 31 is designed to provide the advantage in that a small portion

of the refrigerant contained therein may be changed to condensate and the heat absorbed by the refrigerant from the motor and required to reheat this liquid upon its reentry into the compressor dome as illustrated in Fig. 4 and which will be more fully described hereinafter, will further reduce the operating temperature of the motor compressor unit, thereby to provide reduction in head pressure, improved torque feed performance of the motor and improved operating efficiency of the motor.

Attention is directed to Fig. 1 wherein the condenser 30 with which the present invention is particularly concerned is illustrated in its operative position in conjunction with a compressor A and secured to the back wall 40 of a refrigerator and arranged at a slight angle as shown, the importance of which will be hereinafter described in detail, said back wall of the refrigerator being disposed in spaced relationship to a wall 41 of a house or the like to provide therebetween an air tunnel 42 through which air currents may pass for contact with portions of the condenser by convection.

In the exemplary embodiment of the invention depicted in Figs. 1, 2 and 3, the condenser 30 with which the present invention is particularly concerned comprises, in general, a first serpentine shaped coil 31 herein before described as being a part of a cooling device for the motor-compressor unit, and a series of serpentine shaped coils generally indicated at 45 adapted to receive the refrigerant from the head of the motor housing 20 in order to cool the same and dissipate the heat before the refrigerant is directed to the evaporator, said coils 31 and 45 having welded thereto in staggered relationship as shown a plurality of rods generally indicated at 47, said rods being disposed in thermal contact with the coils 31 and 45 in order to provide additional surface area for contact with the air currents flowing therethrough thereby to provide a more effective heat transfer by convection.

Brackets 51, 52, 53 and 54 are suitably secured to the rods as shown and these brackets are provided with means for securement thereof to brackets 55 and 56 carried by the rear wall 40 of the refrigerator.

Particular attention is directed to Figs. 3 and 5 which show the general relationship of the coils 31 and 45 with respect to the rods 47. These rods are disposed in staggered relationship so that the air currents flowing therethrough will define a foil section air flow (Fig. 5) to more effectively wipe the surfaces of the coils 31 and 45 and the rods 47 because the air currents may pass through these elements without unusual restriction and absorb heat therefrom more effectively because all of the surfaces of these elements are clearly exposed to the naturally flowing air currents and after the air currents have wiped the surfaces of one element they pass off and away from any of the other elements without coming in contact therewith, this action will prohibit any heat taken off one element from being deposited on an adjacent element. Moreover, the air currents will be cooler in that the flow through the elements is natural and unrestricted.

Heretofore, condensers were constructed with finned elements having a substantial area because it was thought that the more area provided for contact with the air currents the more effective would be the transfer of heat from the elements to the air flowing therethrough. These

prior art finned condensers were effective so long as air was forced through the condenser by means of fans or the like which would assure proper wiping of all the surfaces of the fins.

It has been found desirable in refrigeration construction of recent manufacture to eliminate forced air systems and the like and to rearrange the elements of the refrigerating system for more effective employment of space in the food storage compartment. Employment of the prior art finned condensers for contact with natural flowing air currents by convection has resulted in less efficiency in that it has been found that the surfaces of the finned elements, although of substantial area, would not be wiped to advantage by the natural flowing air currents thus resulting in a less efficient system. A conventional finned condenser is illustrated in Fig. 7 and may comprise fins F in contact with tubing T.

Because of the inherent characteristics of construction of the finned condenser in providing isolated channels (Fig. 7) through which the air currents must flow, it was found that the heat was not dissipated from the condenser and that the finned elements provided certain chambers which locked or directed the flow of air in a streamline path as shown in Fig. 7 which resulted in directing the air away from much of the exposed areas of the fins to cause overheating of the condenser and a substantial reduction in the heat transfer from the condenser to the air currents.

In the present invention the deficiencies found in the prior art finned constructions have been overcome in that the natural air currents define a foil section about the rods 47 and are free to flow through the condenser and to wipe thoroughly all of the surfaces exposed which tend toward a more efficient dissipation of heat from the condenser to the air currents.

In reviewing Fig. 1 it can be seen that the air currents enter from the bottom of the refrigerator for passage upwardly through the tunnel 42 into contact with the condenser 30 by convection which is a disturbance of the atmospheric equilibrium by ascensional and expanding heated air, thus causing a wind system by the underflow of cooler air. Since heated air by its nature will flow upwardly the air currents drawn through the tunnel 42 will flow upwardly drawing fresh air from underneath the refrigerator in the direction indicated by the arrows. Particular attention is directed to the angular disposition of the condenser 30 with respect to the rear wall 40 of the refrigerator. This angular disposition permits more effective wiping of the coils 31 and 45 and the rods 47 by the air currents flowing through the tunnel 42. Moreover, after the air currents have contacted the condenser elements to define a foil section air flow, it flows outwardly therefrom (Fig. 5) and is free to continue its flow upwardly in the tunnel 42 without recontacting any of the elements of the condenser. This is important in that once heat has been dissipated from the condenser elements to the air currents it is never redeposited on any of the condenser elements. Furthermore, this action results in a rapid dissipation of the heat from the condenser elements to the air currents. Another important advantage is that the dissipation of heat from the condenser elements to the air currents is more uniform over the entire area of the condenser in that fresh air currents contact all of the surfaces uniformly and, after such contact, leave

the condenser area for passage upwardly through and out of the tunnel 42.

Thus, it can be seen that substantial exposed areas of the prior art finned type constructions (Fig. 7) are not necessary when smaller areas are employed effectively and efficiently so that the entire area thus exposed is thoroughly wiped by the air currents (Fig. 5) which results in a rapid dissipation of the heat from the condenser to the air currents by convection.

In some applications it may be to advantage to employ a condenser tubing 60 of irregular shape as illustrated in Fig. 6. The condenser rods 61, which may be of substantially similar construction to that disclosed with respect to the rods 47 of the condenser construction depicted in Fig. 3, may be suitably welded to the tubing 60 in the undulations defined by the irregular shape of the tubing 60. The importance of the irregular shape in the condenser tubing is obvious in that turbulence in the gas flow will be caused to result in a better K factor for superheated and saturated refrigerant vapor. It has been found that when the flow of the refrigerant vapor through the tubing is disturbed better wiping contact action with the surfaces of the tube is established and therefore a more efficient heat transfer from the refrigerant to the tubing is accomplished.

The instant condenser construction being formed of relatively simple parts facilitating ease in assembly and maintenance lends itself to mass production manufacturing principles, thus affording a substantial saving in the manufacturing cost and a substantial saving in repair and maintenance.

From the foregoing disclosure, it may be observed that I have provided an improved condenser construction which may be employed to advantage, for example, to a refrigerating system and which efficiently fulfills the objects thereof as hereinbefore set forth and which provides numerous advantages which may be summarized as follows:

1. Structurally simple, efficient and durable;
2. Economical to manufacture and readily adaptable to mass production manufacturing principles; and
3. The provision of an improved condenser construction by eliminating expensive finned prior art condenser arrangements and employing a plurality of relatively inexpensive rods disposed in thermal contact with the tubes of the condenser, this construction affording a substantial reduction in the cost of manufacture and yet providing more efficient dissipation of heat by convection.

While I have illustrated preferred embodiments of my invention, many modifications may be made without departing from the spirit of my invention, and I do not wish to be limited to the precise details of construction set forth but wish to avail myself of all changes within the scope of the appended claims.

I claim:

1. In a refrigerating system, having an evaporator and casing means forming a chamber within which a compressor is disposed, a refrigerant superheat removing coil, an outlet from said coil discharging the partially cooled refrigerant into the chamber, a condenser, an outlet from the chamber through which the compressed refrigerant is discharged into said condenser, fluid flow connections between said condenser, evaporator, and compressor, said condenser comprising a serpentine coil adapted to contain refrigerant, means

mounting the loops of said serpentine coil and superheat removing coil in substantially a single plane disposed at a small acute angle to the vertical, and the means providing additional surface area for contact with air currents comprising a plurality of straight rod-like elements, means mounting some of said elements in contact with first surfaces of said serpentine and superheat coils each of which first surfaces face in the same direction, and means mounting the remainder of said elements in contact with surfaces of said coils opposite to said first surfaces and in staggered relationship to said elements in contact with said first surfaces of said coils whereby air currents passing upwardly and through said condenser by convection define a foil section to wipe the surfaces of said coils and said rod-like elements.

2. Refrigerating apparatus comprising a motor compressor unit for increasing the pressure of refrigerant fluid exhausted from a refrigerant evaporating unit and a housing enclosing said motor compressor unit provided with a chamber, a first condenser for receiving the fluid discharged from the high side of the compressor and having communication with the chamber for delivering liquid refrigerant and gas thereto for absorbing heat generated by the motor compressor unit, and a second condenser connected to the chamber for receiving the refrigerant therefrom and converting it into liquid refrigerant, said second condenser forming a part of said first condenser,

means mounting said first and second condensers in substantially a single plane disposed at a small acute angle to the vertical, and means providing additional surface area for contact with air currents comprising a plurality of straight rod-like elements, means mounting some of said elements in contact with first surfaces of said condensers each of which first surfaces face in the same direction, and means mounting the remainder of said elements in contact with surfaces of said condensers opposite to said first surfaces and in staggered relationship to said elements in contact with said first surfaces of said coils whereby air currents passing upwardly and through said condensers by convection define a foil section to wipe the surfaces of said rod-like elements.

JAMES R. HORNADAY.
